UNITED STATES PATENT OFFICE

2,518,627

BUBBLE GUN AND HOLSTER THEREFOR

Robert Lorenz, Denver, Colo.

Application February 7, 1946, Serial No. 645,992

17 Claims. (Cl. 46—8)

1

This invention relates to improvement in toys and particularly to toys for bubble blowing.

It is an object of the invention to provide a toy which can be readily held in and operated by one hand for the purpose of blowing bubbles.

A further object is to provide in combination with such a bubble blower, a holder for such blower adapted to supply the blower with bubble fluid.

A further object is to adapt an air gun to use as a bubble blowing gun.

A further object is to provide an attachment for, or addition to, an air gun whereby such gun may be used for blowing bubbles.

Other objects will hereinafter appear.

With such objects in view, all of which will hereinafter be more fully disclosed, the invention comprises certain novel constructions, combinations and arrangements of parts as will now be fully described and as will be defined in the appended claims and as illustrated in the accompanying drawing in which

Figure 1 is a top or plan view of the bubble gun.

Figure 2 is a vertical, central section of the same showing the piston and associated parts in rearward position ready for bubble blowing action.

Figure 3 is a fragmentary view on same lines as Figure 2 but showing the piston and associated parts in foremost position after "firing," and

Figure 4 is a front end elevation of the bubble gun.

Figure 5 is an elevation of my improved holster with bubble fluid supply and illustrating the gun, partly in broken lines, in position in the holster.

The gun is preferably formed, for convenience and efficiency, in conventional pistol shape with a handle 5 carrying an air cylinder 6, simulating, in both form and position, the cartridge cylinder of a revolver, from which cylinder tube 7 projects forwardly, simulating, in form and position, the barrel of a revolver. The front end of tube 7 is closed, as at 8 but the closure is provided with a small central orifice 9 adapted to emit a stream or jet of air when the device is operated in a manner later described.

The bubble assembly is mounted on the front end of tube 7 and comprises a ring 10 carried between the front ends of bars 11 whose rear ends are mounted on the front end of tube 7, by soldering or other suitable means, as indicated at 12. It will be understood that the center of ring 10 and orifice 9 should be aligned with the cen-

tral longitudinal axis of tube 7, or parallel therewith.

Cylinder 6 is provided with a piston 13 whose rod 14 projects through the rear wall 6a of the cylinder and, therebeyond is provided with coiled spring 15 seated between and against wall 6a and stop 16a carried by rod 14, whereby the normal expansion of spring 15 will retract piston 13 to the rear of the cylinder as shown at Figure 2.

Trigger 16 is pivotally mounted in the forward part of handle 5 as at 17, the lower portion 18 forming a finger piece and the upper portion 19 being provided with an arcuate slot 20 adapted to engage pin 14b carried by rod 14, whereby the retraction of finger piece 18 will move rod 14 and piston 13 forward to the position shown at Figure 3. The rear end of rod 14 is preferably slidably mounted in a guide 21 carried by handle 5.

Front and rear sights 22 and 23 are shown only for symmetry and ornamentation and form no part of the invention. The usual trigger guard 24 is shown for like purpose and is no part of the invention.

In operation the elements are in normal position as shown at Figure 2, the cylinder 6 being filled with air in front of piston 13. Ring 10 is dipped in some suitable bubble forming solution which forms a film across the ring. Finger piece 18 is drawn back forcing piston 13 forward and forcing a jet of air through and forwardly from orifice 9, which jet will contact the center of the film across ring 10 bending the film outwardly and forming a bubble in a manner well understood.

The spacing of the ring 10 with respect to the point of air emission from the orifice 9 controls the velocity at which the air stream strikes the film of bubble forming liquid and in order to accomplish the results, this spacing

must be within definite limits. The spacing of the film of liquid with relation to the point of air emission is such that the velocity of the air stream striking the film is sufficient to form and project a bubble or bubbles forwardly from said

film but yet the velocity is not sufficient to break entirely through the film without the formation of a bubble. In addition to permitting a control of the velocity of the air stream at the time that said stream strikes the film, the air space be-

tween said film and the orifice 9 functions to nullify any suction effect which might be produced upon the back stroke of the piston, which suction might break the film and displace it from the ring. In other words, upon the back

stroke of the piston air may be drawn into the

cylinder through the orifice with said air entering the orifice behind the film and without creating any suction against the rear surface of said film. With the right solution and practice in operation of this device a number of bubbles may be blown from the ring successively during a single complete forward stroke of piston 13.

While the bubble gun may be used wherever there is a supply of bubble liquid in which to dip the ring 10, its preferred use is as a part of the 10 complete toy comprising the gun and a liquid-carrying holster now to be described.

A holster 25 is provided, preferably provided with a belt 26 for attaching the holster to the person, the holster and gun being so relatively formed and proportioned that the gun will rest in the holster as indicated at 27 and 28. The bottom end of the holster terminates in a liquid container 29 suitably secured to the holster preferably threaded as conventionally indicated at 30, the container being so proportioned and positioned that ring 10 of the gun will, when the gun is seated in the holster, be suspended in the liquid 29 near the bottom of the container so as to be submerged therein whenever there is any substantial quantity of liquid in the container without touching, during insertion into, withdrawal from, or rest within the container, either the bottom or the walls of the container.

Thus, whenever there is any substantial quantity of bubble liquid in the container the gun may be carried in the holster and at any time withdrawn for use in blowing bubbles, a film of bubble liquid always adhering to and covering ring 10 when withdrawn, thus rendering the gun ready for bubble blowing immediately upon withdrawal from the holster.

While I have illustrated and described many details of construction and arrangement of parts I am not to be restricted thereto and desire protection as well upon those equivalent or alternative structures and arrangements which will occur to those skilled in the art and which are within the spirit of the invention as herein disclosed and the spirit and scope of the appended claims.

I claim:

1. A toy comprising a handle, a cylinder carried by and forwardly of the handle, a piston in the cylinder having a piston rod projecting rearwardly from the cylinder, a trigger carried by the handle and operatively engaging the rod and adapted to move the piston to compress air in the cylinder, a conduit of substantially less than half the transverse area of the cylinder leading forwardly from the cylinder, the front end of the conduit being closed except for a small orifice in the center of the closure and a ring carried by the conduit, the center of which is aligned with the longitudinal axis of the conduit and which ring is spaced substantially forwardly from said closure.

2. In a device as defined in claim 1, resilient means for normally holding the piston at the rear of the cylinder.

3. In a device as defined in claim 1, said conduit being tube-like and leading from the upper forward end of the cylinder.

4. In a device as defined in claim 1, said rod carrying a stop and a coiled compression spring enclosing the rod and seated between and against the rear wall of the cylinder and said stop.

5. In combination with a device as defined in claim 1, a carrier for said device comprising a case adapted to receive the device and support the same by contact between the case and the device

elsewhere than with the conduit or the ring, said case carrying a container adapted to hold liquid and to receive said ring within said container when the device is seated in the case.

5. In combination with a device as defined in claim 1, a holster-like case adapted to receive and seat said device therein, the lower end of said case being a liquid container adapted to receive therein the said ring carried at the end of said conduit.

7. A bubble blowing toy comprising a tube having a closure with a central orifice at one end, a ring fixedly associated with said tube and spaced outwardly from said closed end of said tube, the center of the ring being at the extended longitudinal axis of the tube and means for compressing air in the tube whereby to project a jet of air from said central orifice toward the center of the ring.

20. 8. In combination with a device as defined in claim 7, a carrying case adapted to receive said device when positioned with said ring directed downwardly, said case carrying a liquid container at its lower end and being adapted to receive and support said device in position with said ring within said container.

9. A bubble gun, comprising a stock and barrel structure, a film of bubble forming solution supported at the end of the barrel on a support therefor, combined means within the stock and barrel structure for intermittently discharging bubbles from the film support.

30. 10. A bubble forming gun comprising a film support for a bubble forming solution, self contained means comprising a pressure trigger within the gun for producing and discharging a succession of bubbles when a film of the solution is carried on the film support when normal operating pressure is applied to the pressure trigger.

40. 11. The combination with a toy gun having means for producing and emitting a stream of air through its barrel, of a bubble liquid retaining member mounted forwardly of the point of emission of the air stream and disposed in spaced relation to said point of emission, said member being adapted to retain a film of bubble liquid thereacross, the spacing of said member and film with respect to said point of emission of said air stream being within definitive limits determined by the volume and velocity of the air stream, said spacing being such that when the air stream strikes the film its velocity is only sufficient to form and project a bubble from the member but is not sufficient to entirely displace the film from the member without the formation of a bubble.

12. The combination with a toy gun having means for producing and emitting a stream of air from the outer end of its barrel, of a bubble liquid retaining member adapted to receive and retain a bubble forming liquid thereacross and disposed in the path of the air stream, the member being spaced from the point of emission of the air stream whereby a free circulation of air around and rearwardly of the member is permitted to obviate any suction being formed rearwardly of the film on said member, the spacing between said member and the point of emission of the air stream being such as to control the

70. 75. velocity of the air stream striking the film, such velocity being such that the air stream functions to form and project a bubble forwardly from the member without entirely displacing the film with the formation of a bubble upon each actuation of the gun.

13. A toy including, a tubular conduit, a bubble liquid retaining member mounted forwardly of the outlet end of the conduit for receiving and retaining a film of bubble forming liquid thereacross, and means for producing and directing a stream of air through said conduit and against the film on said member, said member and the film carried thereby being spaced from the outlet end of the conduit with the spacing of said member and film with respect to the conduit being within limits determined by the volume and velocity of the air stream, said spacing being such that the air stream emitting from the conduit has sufficient velocity upon striking the liquid film to form and project a bubble from the member and at the same time, does not have sufficient velocity to entirely displace the liquid film from said member without the formation of a bubble.

14. A toy including, a tubular conduit, means for producing and directing a stream of air through said conduit and outwardly therefrom, a bubble liquid retaining member mounted forwardly of the outlet end of the conduit for receiving and retaining a film of bubble forming liquid, whereby the air stream ejected from said conduit strikes the film on said member, said member being in axial alignment with the conduit and being spaced from the conduit with the area between the outlet end of the conduit and the liquid retaining member being substantially unrestricted to allow free flow of air around the member to nullify the possibility of any suction being created behind the film, the spacing between the liquid retaining member and film carried thereby and the outlet end of the conduit being determined by the volume and velocity of the air stream, said spacing being such that the air stream striking the liquid film has sufficient velocity to form and project a bubble forwardly from the member and yet does not have sufficient velocity to displace the film from the member without the formation of a bubble.

15. The combination with a toy gun having means for emitting a stream of air through its barrel, of a bubble-liquid-retaining member comprising a substantially continuous ring mounted forwardly of the point of emission of the air stream and secured to the forward end of the gun barrel by a supporting medium which does not restrict the air stream, said ring being adapted to retain a film of bubble-forming liquid thereacross, the spacing of said ring and film with respect to said point of emission of said air stream being within definite limits determined by the volume and velocity of the air stream, said spacing being such that when the air stream strikes the film its velocity is only sufficient to form and project a bubble from the member but is not sufficient to entirely displace the film from the member without the formation of a bubble.

16. A toy, including a tubular conduit, a bubble-liquid-retaining member mounted forwardly of the outlet end of the conduit for receiving and retaining a film of bubble-forming liquid

thereacross, means for directing a stream of air through said conduit and against the film on said member, said member and the film carried thereby being spaced from the outlet end of the conduit, the spacing of said member and film with respect to the conduit being within limits determined by the volume and velocity of the air stream, said spacing being such that the air stream emitting from the conduit has sufficient velocity upon striking the liquid film to form and project a bubble from the member and, at the same time, does not have sufficient velocity to entirely displace the liquid film from said member without the formation of a bubble, and a carrying case adapted to receive said toy when positioned with said retaining member directed downwardly, said case having a liquid container at its lower end and being adapted to receive and support said toy in position with said member within said container.

17. A toy, including a tubular conduit, means for directing a stream of air through said conduit and outwardly therefrom, a bubble-liquid-retaining member mounted forwardly of the outlet end of the conduit for receiving and retaining a film of bubble-forming liquid, whereby the air stream ejected from said conduit strikes the film on said member, said member being in axial alignment with the conduit and being spaced from the conduit, the area between the outlet end of the conduit and the liquid retaining member being substantially unrestricted to allow free flow of air completely around the member to nullify the possibility of any suction being created behind the film, the spacing between the liquid retaining member and film carried thereby and the outlet end of the conduit being determined by the volume and velocity of the air stream, said spacing being such that the air stream striking the liquid film has sufficient velocity to form and project a bubble forwardly from the member and yet not sufficient velocity to displace the film from the member without the formation of a bubble, and a carrying case adapted to receive said toy when positioned with the retaining member directed downwardly, said case having a liquid container at its lower end and arranged to receive and support said toy in position with said member within said container.
